ATTORNEYS

UNITED STATES PATENT OFFICE.

ELIZABETH J. KENNEDY, OF PHILADELPHIA, PENNSYLVANIA.

HOUSEHOLD IMPLEMENT.

Application filed January 25, 1923. Serial No. 615,420.

To all whom it may concern:

Be it known that I, ELIZABETH J. KENNEDY, a citizen of the United States, and a resident of the city and county of Philadelphia, State of Pennsylvania, have invented certain new and useful Improvements in Household Implements, of which the following is a specification, reference being had to the accompanying drawing.

- 10 Among the principal objects of my invention are to provide an implement which may be conveniently employed in washing clothes or other articles both in the operation of applying the soap to the articles to be washed and in the subsequent operation of rubbing the articles; to provide an implement which renders it unnecessary for the operator to immerse the hands in the wash water in the operations of soaping and rubbing the clothes and to provide an implement embodying novel means for holding a cake of soap in combination and association with other means for facilitating the operations in which the implement is intended to 25 be employed as aforesaid.

Further objects of my invention are the provision in a household implement of soap holding means of such character that the likelihood of injury to the fabrics to which 30 the soap is applied is minimized, and to provide a household implement suitable for use in and adapted to facilitate the operation of washing clothes or other articles which is simple in construction, easy to use and may 35 be manufactured at a relatively low cost.

The foregoing, as well as various other objects and novel features of construction and arrangement comprehended by my invention, will more fully appear from the following description taken in connection with the drawing forming a part hereof and in which are illustrated certain embodiments of the invention.

In the said drawing in which the same numerals are used to indicate similar parts in the several figures, Fig. 1 is a perspective view of a preferred embodiment of my invention with the parts in the position in which they are disposed under operative condition and with a cake of soap shown in broken lines in operative position in the implement, and Fig. 2 is a fragmentary longitudinal, vertical, substantially central section thereof, also illustrating in dotted lines 55 substantially the position assumed by one of

the elements of the soap holding means when in non-operative or non-soap-holding position. Figs. 3 and 4 are views substantially similar to Fig. 1 but with the implement handle broken away and respectively showing slightly modified forms of the invention, while Fig. 5 is a similar view of a further slightly modified form as will hereafter more fully appear.

Referring now more particularly to the form of the invention shown in Figs. 1 and 2, the same may preferably comprise a body, generally designated as 2, having a substantially rectangular portion 3, terminating in a transversely extending lower edge or end 3', and which at its other or upper end merges into and is continued upwardly to form a handle 4 of a shape to be readily grasped by the operator. Conveniently this body may be cut from a board of suitable thickness so as to present substantially flat parallel opposite faces 5 and 6, the former being adapted toward the lower end 3' of the body to form a seat or supporting surface for a cake of soap S when disposed in the implement as hereinafter described. Preferably I may provide adjacent the lower extremity 3' of the body and disposed transversely thereof so as to extend outwardly from the face 6, a cross member 7 forming a rubbing element 8, conveniently formed separately from the body and rigidly secured thereto in any suitable manner. This rubbing element is conveniently provided with a curved surface or extremity 9 in such manner that during the washing operation the element may be rubbed over the clothes to remove the dirt or stains therefrom without danger of tearing or otherwise injuring the delicate fabric. In the preferred embodiment of the invention this rubbing element is preferably long enough to extend entirely across the body and thus assists, in addition to its primary function, in stiffening and strengthening the body.

Suitable means are provided for maintaining a cake of soap S in the implement and preferably adjacent the lower extremity 3' of the body, said means in the preferred embodiment of the invention comprising a transversely extending stop or abutment 10 rigidly secured to the body and extending transversely thereof and outwardly from the face 5 in combination with means for hold-

ing the soap on the implement and in the angle formed between the lower face of the stop and the surface of the body. Conveniently said last mentioned means may comprise a flexible element 12 preferably formed from spring wire and secured at one end in the body so as to extend upwardly and generally rearwardly from a point about midway between the stop and the end 3', and means for receiving and operatively locking the opposite end of the flexible means to the body in the vicinity of the point where the latter merges into the handle. While the said receiving and locking means may be of any suitable form, the same may conveniently comprise a recess 13 formed in the body and of a suitable size to receive and retain the free end of the flexible element when inserted therein. Ordinarily this recess may be formed by drilling a hole in or through the body at the proper point, the axis of the hole being inclined with respect to the surface of the body so as to facilitate the introduction of the end of the flexible element when desired. The other end of the element is permanently secured in or to the body in any suitable manner conveniently by passing the same through a hole 15 drilled through the body in a more or less angular direction about midway between the end 3' and the stop and preferably on the center line of the body, and then bending the extremity 12' of the element back upon itself and driving it into the face 6 of the body in the manner clearly shown in Fig. 2. It is found in practice that this method of fastening the flexible element in the body may be cheaply and rapidly carried out and is entirely satisfactory for the performance of the requisite function, but other methods of securing the end of the flexible element in or to the body may be utilized if desired.

By reason of the fact that the flexible element 12 is formed of spring wire or the like, when its free end is removed from the recess 13 or other securing means, the element will normally assume a position substantially as indicated in dotted lines in Fig. 2 and may if desired be readily sprung or bent to a position more nearly at right angles to the body without imparting to it a permanent bend or set. When it is desired to position a cake of soap on the implement therefore, the element is sprung upwardly and forwardly (that is, in a direction away from the handle) from the position shown in dotted lines in Fig. 2 to one in which it may be more conveniently pushed through the cake of soap, ordinarily at substantially the center thereof, after which the cake is slid down the element till it contacts with the surface 5. The element is then sprung rearwardly and downwardly until its free end can be secured to the body as by insertion in the recess 13, which operation results in drawing

the cake snugly against the stop 10, in which position it is thereafter securely maintained as long as the free end of the flexible element is secured to the body. If desired either the implement or the soap or both may be dipped in water before the soap is placed in position as it is found that with certain varieties of soap initial wetting of the contacting surfaces of the soap and the implement enhances the rigidity with which the soap is held in operative position, but ordinarily such preliminary wetting may be dispensed with.

It will be observed that with the soap thus positioned in the angle between the forward face of the stop and the surface of the body, the soap may be very conveniently applied to the clothes or other articles being washed by grasping the handle and holding the implement in a position in which the soap may be rubbed thereagainst and that even after the soap is considerably worn away so as to allow a greater length of the flexible element to be exposed than is initially the case when the soap is first positioned in the implement, there is no danger of tearing or otherwise injuring the clothes since the surface presented by the flexible element is always smooth and devoid of sharp corners or the like. It will of course be apparent that in the course of time the soap will be worn away to a point at which it can no longer be conveniently applied, after which the free end of the flexible element may be removed from the recess and any portion of the soap remaining between the stop and the body removed and a fresh cake inserted in the manner already described.

In the modification of the invention shown in Fig. 3 I may provide the body 1 between its lower extremity 3' and the face of the stop with one or more blades 18, for example, a pair of blades disposed at right angles to each other and intersecting at their centers, a portion of each blade being disposed in a slot or recess formed in the surface 5 and the other portion of the blade projecting outwardly therefrom, while in the modification shown in Fig. 4 I provide instead of blades, one or more pins 19 arranged to project above the surface 5 between the face of the stop and the extremity of the body, preferably in either construction the height of the blades or the pins being considerably less than the height of the stop. In utilizing these forms of the invention the cake of soap is placed in contact with the stop and then forced downwardly toward the face 5 and into the angle between the stop and the surface of the body in such manner that the blades or the pins will enter the cake and assist in retaining the same in position in the implement. By reason of the fact that the blades or pins are preferably relatively short it will be apparent that the extremi-

ties thereof will not be exposed until the major portion of the cake has been worn away thus obviating any injury to the clothes.

In the form of the invention shown in Fig. 5 instead of employing a transversely disposed stop 10 to engage the end of the cake of soap, I may utilize a plurality of pins 20 arranged in laterally spaced relation to project outwardly from the face 5 of the body at a suitable distance from the end 3 thereof, the function of these pins, namely, that of forming an abutment or stop for the end of the cake, corresponding to the function of the preferred form of stop 10 hitherto described. Obviously, if desired, pins of this character may be used in place of the stop 10 in connection with the forms of the invention shown in Figs. 3 and 4.

It will thus appear that my invention provides an implement adapted for use in washing clothes or other articles and in other similar household operations and by means of which a cake of soap may be conveniently held and applied to the goods being washed or may be shaken to form a lather in the wash water and which also may be utilized for rubbing the clothes to remove the dirt therefrom, all without the necessity of the operator dipping the hands in the water or in fact, bringing the hands into contact with the clothes at all, these features contributing to the marked utility of the device and being especially appreciated when badly soiled clothing or articles from sick rooms are being laundered with consequent desirability of minimizing the contact of the operator's hands therewith or their introduction into the wash water.

While I have herein described with considerable particularity a preferred and certain modified forms of my invention I do not thereby desire or intend to specifically limit the invention thereto, as minor changes may be made in the form, construction and

arrangement of the several parts entering thereinto without departing from the spirit and scope of the invention as defined in the appended claims.

Having thus described my invention, I claim and desire to protect by Letters Patent of the United States:

1. A device of the class described, comprising a body, a handle extending from one end thereof, a stop projecting substantially normal to a face of the body between the handle and the other end thereof, and flexible means extending from the body at a point between said other end and the adjacent side of the stop adapted to be inserted in a cake of soap. 60

2. A device of the class described, comprising a body, a handle extending from one end thereof, a stop projecting substantially normal to a face of the body between the handle and the other end thereof, flexible means extending from the body at a point between said other end and the adjacent side of the stop adapted to be inserted in a cake of soap, and means for removably securing an end of said flexible means to the body on 70 the opposite side of said stop. 70

3. In a device of the class described, the combination of a body having a handle extending from one end and a substantially flat face, a stop projecting substantially 75 normally outward from said face and disposed between the handle and the opposite end of the body, a spring wire secured at one end in the body and extending from the face thereof between the abutment and the end of the body and normally curving outwardly from said face and toward the handle, and means for securing the free end of the wire to the body at a point adjacent the handle. 80

In witness whereof, I have hereunto set my hand this 23rd day of January, 1923.

ELIZABETH J. KENNEDY. 85
